(57) **CLAIM**

The ornamental design for a body of nail clipper as shown and described.

DESCRIPTION

FIG. 1 is a perspective view of a body of nail clipper, showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is an enlarged view of a portion of the body of nail clipper shown within the area designated as 8 in FIG. 2. The dash-dash broken lines in the drawings show portions of the body of nail clipper that form no part of the claimed design. The dot-dash lines encircling portions of the body of nail clipper in FIG. 2, and illustrated in the enlarged views in FIG. 8, form no part of the claimed design.
